UNITED STATES PATENT OFFICE.

JAMES FITTON, OF CAVENDISH, VERMONT.

CARDING-ENGINE.

Specification of Letters Patent No. 30,875, dated December 11, 1860.

To all whom it may concern:

Be it known that I, JAMES FITTON, of Cavendish, in the county of Windsor and State of Vermont, have invented a new and useful combination of mechanism with a carding-engine for the purpose of returning to the action of the carding mechanism, the droppings of fibrous material therefrom, and separating from those droppings a large portion of the foreign matter which is mixed with them; and I do hereby declare that the following, taken in connection with the drawing which accompanies and forms part of this specification, is a description of my invention so full and exact as to enable those skilled in the art to practice it.

The drawing is a side view, or elevation, illustrating so much of the ordinary carding engine as is necessarily referred to in describing my invention, and the addition which I make to the carding engine.

A represents the tumbler roll, B the card clothed cylinder, and C the doffer roll. These are mounted as usual upon a suitable frame H, to which also rolls E and F are connected, over which passes the apron D, the first of these rolls being the driving roll which actuates the apron and which receives its rotation from the doffer roll shaft by means of a band, or it may be rotated in any other convenient manner. The apron consists of wooden slats, which are made somewhat convex on the surface which comes next to the card cylinder, and which are secured, at small intervals apart, to bands which pass around the rolls E and F. The apron is best made of such length and width as to extend under the entire space occupied by the tumbler and doffer rolls and the card cylinder, so that any droppings from these will fall upon the apron. A gage roll G passes under the apron at the line where the latter comes nearest into contact with the teeth of the card cylinder.

This roll is connected to the frame by hang-
ers or bearings which admit of raising or
depressing the roll G so as to gage the dis-
tance from the convex surface of the slats
to the card teeth. It is well known that the
fiber of wool is bearded, which enables it
to be felted, and to cling to any body with
which it may come into contact. It is the
latter property which enables me to make
use of the endless apron in connection with
a carding engine for the purpose before
named. As the fibers and locks of wool fall
upon the slats the strong current of air pro-
duced by the rotation of the card cylinder
forces them upon the slats, where they cling
till they come into contact with the card teeth
which removes them from the slats and sub-
jects them to the action of the carding mech-
anism. The fibers not only lay on the parts
of the belt which are uppermost, but cling
to them in their inverted position. The par-
ticles of foreign matter, which are lacking in
the bearded formation, and are of greater
specific gravity than is the wool, drop from
the apron through the spaces between the
slats, or fall off of them as they pass around
the rolls, or as they move in the inverted
position. It is best to cause the cylinder and
the apron to move in different directions,
and at widely varying rates of speed. The
position of the apron is a matter of little or
no importance as to whether it is horizontal
or inclined, so long as there is one point in
it which can be adjusted to the proper dis-
tance from the teeth of the card cylinder.

I claim—

The combination of an endless traversing
apron, with the cylinder of a carding en-
gine, operating substantially in the manner
set forth.

JAMES FITTON.
